TUBE CLOSURE

Gustave R. Osterholm, Hartford, Conn.

Application July 5, 1939, Serial No. 282,895

3 Claims. (Cl. 221—60)

This invention relates to improvements in closures and especially is concerned with a novel closure for collapsible containers such as tubes for shaving cream or the like.

It is an object of the present invention to provide a novel closure which, although characterized by simplicity of construction, nevertheless is positive in action and which moreover includes no separate parts which might, upon occasion, be lost during use of the closure.

Another object of the present invention is to provide a closure including a pair of cooperating reciprocating opposed seal elements movable by oscillation of a cap and suited to controlling discharge of materials from a container associated therewith.

Another object of this invention is to provide a novel closure which, by reason of its structure, is well suited to the requirements of mass production and which can be made, if preferred, entirely from plastics by conventional molding processes.

An advantage of the closure according to this invention is that it can be opened or closed by the user's same hand that is used for holding the tube.

Another advantage of the closure according to this invention is that, as hereinabove mentioned, the closure does not include separable parts which might be lost during use of the closure and container.

A noteworthy feature of the novel closure according to this invention is that the appearance of the closure harmonizes with the appearance of the container end whereby aesthetically satisfying assembly having a pleasant appearance without sacrifice of utility is achieved.

Other objects, advantages and features of the new and improved closure according to the present invention will be apparent to those skilled in this art during the course of the following description.

Regarded in certain of its broader aspects the novel closure according to this invention comprises a neck formed integral with a container and provided with an axially extending discharge passage terminating in a discharge orifice at the end of the neck; ways diametrically extending across the end of said neck intersecting said orifice; sliding seal elements in said ways; and a cap interengaged with said sliding seal elements for causing movement thereof whereby rotation of the cap relative to the neck causes said seal elements to obstruct or close the discharge orifice or,

upon occasion, to move free of the orifice opening same.

In order to facilitate a fuller and more complete understanding of the present invention a specific embodiment thereof herein illustrated will be hereinafter described, it being clearly understood, however, that the illustrated embodiment, although presently preferred, is provided solely by way of example of the practice of this invention and not by way of limitation thereof except insofar as the invention is recited in the subjoined claims.

Referring then to the drawing:

Figure 1 is substantially a side elevational view of the presently preferred embodiment of this invention, the closure being shown mounted upon portions of a conventional collapsible tube.

Fig. 2 is essentially a top plan view of the device illustrated in Fig. 1.

Figs. 3 and 4 are vertical sectional views of Fig. 2 taken along the lines 3—3 and 4—4 respectively showing the seal elements of the closure in closed and in opened positions respectively.

Fig. 5 is a horizontal sectional view of Fig. 4 taken along the line 5—5, and

Fig. 6 is a horizontal sectional view of Fig. 3 taken along the line 6—6.

Referring now especially to Figs. 2 et seq., of the drawing, it will be noted that the novel closure according to the present invention generally designated by the numeral 10 comprises a neck 11 having rounded end portion 11a and provided with a discharge orifice 11b centrally located in the rounded end 11a and communicating with the discharge passage 11c axially extending through the neck. The opposite end of the discharge passage 11c of course communicates with the interior of the collapsible tube 12 integrally formed with the neck, essentially as shown. Diametrically extending ways 11d intersecting the discharge orifice 11b and extending across the rounded end portion 11a of the neck 11 receive the curved sliding seal elements 13 and 13a which are disposed in opposed relationship and provided with interengaging end portions 13' whereby, when the end portions of the sliding seal elements are interengaged, they overlie the discharge orifice 11b, closing same essentially as shown in Figs. 2, 3 and 5. It is to be noted that the sliding seal elements 13 and 13a are provided with projecting elongate rider lugs 13b and 13c respectively which cooperate with other parts of the device as will be hereinafter described to facilitate movement of the seal elements.

- A hollow cap 14 fitting closely against exterior parts of the neck 11 hereinabove described and having near the base thereof a projecting annular shoulder 14a is freely rotatably held upon the neck by the inwardly turned flange 15 formed integral with parts of the tube 12 and overlying the flange essentially as depicted in Figs. 1, 3 and 4. A discharge port 14b is provided in the cap 14 and is registerable irrespective of the cap relative to the neck with the discharge orifice 11b hereinabove mentioned, whereby, when the seal elements 13 and 13a are moved from the position obstructing the discharge orifice, as illustrated in Fig. 3, to the retracted position, illustrated in Fig. 4, the discharge of materials through the discharge orifice and the discharge port is freely permitted.

The inner rounded surface of the cap 14 overlying the rounded end 11a of the neck 11 is provided, as is best illustrated in Fig. 6, with opposed segmental spiral cam grooves 14d adapted to receive and engage with the projecting rider lugs 13b and 13c formed on the seal elements 13 and 13a respectively.

As will be obvious from the foregoing description, rotation of the cap 14, which readily may be accomplished by gripping the narrow corrugated edge portion 14c thereof, causes the seal elements 13 and 13a to move either into or away from position of engagement depending upon direction of rotation, as the projecting riders 13b and 13c slide in the cam grooves 14d as mentioned.

It is to be noted, as will be obvious upon examination of Figs. 2 and 3, that the abutting interengaging end portions 13' of the seal elements 13 and 13a project slightly outwardly through the discharge port 14b thereby facilitating cleaning of the closure after use.

Having thus described the present invention, what it is desired to secure by Letters Patent is: 1. A closure for collapsible containers comprising a neck integral with the container having a rounded distal end with a discharge orifice centrally located therein and diametrically extending

ways formed in surface parts of said end; opposed interengaging sliding seal elements in said ways for, upon occasion, overlying and closing said discharge orifice; a cap fitted closely against exterior portions of said neck, having a discharge port registerable with the discharge orifice in the neck; and means connecting the cap and the seal elements in a manner such that oscillation of the cap on the neck results in engagement and disengagement of the seal elements with concomitant opening and closing of the discharge orifice the seal elements when in interengaged relation projecting outwardly slightly through said discharge port.

2. A closure for collapsible containers comprising a neck integral with said container having a rounded distal end with a discharge orifice centrally located therein and diametrically extending ways formed in surface parts of said end; opposed interengaging sliding seal elements in said ways for upon occasion overlying and closing said discharge orifice, projecting rider lugs one on each of said seal elements; a cap fitting closely against exterior portions of said neck, having a discharge port registerable with the discharge orifice in the neck, and having formed in internal portions thereof engaging with the rider lugs of the seal elements opposed segmental spiral cam grooves arranged in a manner such that oscillation of the cap on the neck results in reciprocation of the seal elements with concomitant opening or closing of the discharge orifice; and means for freely rotatably holding said cap on said neck comprising an annular shoulder on said cap near the base thereof and a flange mounted on said tube engaging with said annular shoulder.

3. In the combination of a collapsible container end and a closure of the type including an oscillating cap on the closure neck, the improved means for freely rotatably holding the cap on the neck comprising an annular shoulder on the cap near the base thereof and a flange on the tube end engaging the shoulder.

GUSTAVE R. OSTERHOLM. 45
